[57] CLAIM

The ornamental design for a meterological station with sensor array, as shown and described.

DESCRIPTION

FIG. 1 is a front elevational view of a meterological station with sensor array showing my new design;
FIG. 2 is an enlarged front and bottom perspective view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof.

The antenna and support pole of FIGS. 2-5 have been shown broken-away for ease of illustration.

FIG. 2**FIG. 1****FIG. 3**

FIG. 4

FIG. 5

FIG. 6

FIG. 7
